DOOR-SAG CORRECTING MECHANISM

David P. Triller, Indianapolis, Ind.

Application April 22, 1947, Serial No. 743,142

14 Claims. (Cl. 16—82)

1

The present invention relates to devices for correcting door sag, and is particularly concerned with the provision of means, so constructed that it may readily be installed by the average householder, and which shall be inexpensive, easy to install, and easy to adjust after installation. It is an object of the invention to provide simple means which, when installed in the manner contemplated, will act, as a door moves toward its closed position, to force vertical movement of the free edge of the door into a proper horizontal position of adjustment to permit full closure of the door, and/or to effect registration of the door latch with the latch plate on the frame. A further object of the invention is to provide means which will not only overcome sag, but which will also act as holding means to retain the door in closed position or to press the door latch against its socket in the latch plate, to prevent rattling of the door in closed position. Still further objects of the invention will appear as the description proceeds.

To the accomplishment of the above and related objects, my invention may be embodied in the forms illustrated in the accompanying drawings, attention being called to the fact, however, that the drawings are illustrative only, and that change may be made in the specific constructions illustrated and described, so long as the scope of the appended claims is not violated.

Fig. 1 is a fragmental, more or less diagrammatic, perspective view of portions of a door frame and of a door hung therein, with one embodiment of my invention installed thereon;

Fig. 2 is a fragmental elevational view of a portion of the free edge of the door in closed association with its frame, showing the same embodiment of my invention;

Fig. 3 is a sectional view taken substantially on the line 3—3 of Fig. 2, and showing the door just before it reaches fully closed position;

Fig. 4 is a similar view, showing the parts in the relation assumed thereby as the door reaches fully closed position;

Figs. 5 and 6 are views similar to Figs. 3 and 4, respectively, and showing the parts of my invention in a different relationship;

Fig. 7 is a similar view, showing a modified form of my invention, with the door in fully closed position;

Fig. 8 is a view similar to Fig. 7 and showing a slightly modified embodiment of my invention;

Fig. 9 is a view similar to Fig. 3 but showing a still further embodiment of my invention, with the door in partially closed position;

2

Fig. 10 is a view of the embodiment of Fig. 9 with the door fully closed;

Fig. 11 is a view similar to Fig. 10, but showing a modified relationship of the parts;

Figs. 12 and 13 are similar to Figs. 9 and 10, but illustrating a further form of my invention;

Fig. 14 is a similar view, but showing still another embodiment of my invention;

Fig. 15 is a view similar to Fig. 14 but illustrating a still further embodiment of my invention; and

Fig. 16 is a similar view, showing another form of my invention.

Referring more particularly to Figs. 1 to 4, it will be seen that I have illustrated a door 20 hung in a frame 21, said frame including a surface 22 which faces, when the door is closed, the free vertical edge 23 of the door 20. A cylindrical disc 24 is mounted upon the surface 22 by means of a screw 25 constituting a journal element for said disc, concentric to said disc, so that the disc 24 acts as a roller, and is rotatable upon its own axis.

The cylindrical surface 26 of the disc 24 is so positioned as to be engaged, as the door 20 moves toward closed position, by the cylindrical surface 27 of a second disc 28 secured to the free edge 23 of the door by means of a screw 29 which penetrates said disc eccentrically upon a line parallel with the axis of said disc and with the surface 27. That surface of the disc 28 which abuts the door surface 23 is provided with axially extending projections which may be simple burrs, but which, when the screw 29 is solidly set, will bite into the surface of the door edge to retain the disc 28 against rotational movement about the axis of the screw 29. However, before the screw 29 is solidly seated, the disc 28 will obviously be rotationally adjustable about the axis of said screw, thereby adjusting the degree of projection of the surface 27 below the horizontal line intersecting the axis of said screw.

As the door approaches closed position, the cam surface 27 of the cam disc 28 will engage the surface 26 of the disc 24, in the manner illustrated in Fig. 3; whereupon further movement of the door in closing direction, will cause the disc 28 to be cammed upwardly, as the disc 24 rotates in a counter-clockwise direction as viewed in Figs. 3 and 4. In Figs. 3 and 4, the reference lines H and L, represent, respectively, the high and low positions of the axis of the screw 29, resulting from the coaction of the discs 24 and 28, when the disc 28 is in its illustrated position of adjustment; and the distance between said

lines H and L represents the degree of sag correction effected by the illustrated device.

In accordance with standard practice, the frame 21 includes a surface 31 facing in the direction of door-opening movement; and engagement of the door 20 with said surface 31 limits closing movement of the door. In the embodiment of the invention illustrated in Figs. 1 to 4, it will be noted that, when the door engages the surface 31, the vertical diameter of the disc 24 is located between said surface 31 and the vertical diameter of the disc 28, so that the sag tendency of the door exerts a door-opening force through the coaction of the surfaces 26 and 27. That force will hold the door latch forcibly against the wall of its socket in the latch plate to retain the door against rattling.

It will be clear that, because of the provision of the eccentric mounting for the disc 28, accurate positioning of the screws 25 and 29 is not necessary. The householder may guess at the approximate amount of sag; secure the disc 24 to the frame 22; and thread the screw 29 into the door edge 23 at approximately the right level. Then, swinging the door toward closed position, he ascertains, by inspection, the approximately correct position of rotational adjustment of the disc 28, sets the disc at that position, solidly seats the screw 29, and again tries the effect of closing the door. If he finds that the door edge is lifted too far, he adjusts the disc 28 in a counter-clockwise direction; or if it is not lifted far enough, he adjusts the disc 28 in a clockwise direction. This "try-and-set" cycle is repeated until the proper adjustment of the disc 28 is attained.

In Figs. 5 and 6, I have shown the disc 28 oppositely set. That is, in the arrangement of Figs. 5 and 6, the vertical diameter of the disc 28, when the door is fully closed, is located between the surface 31 and the vertical diameter of the roller 24, whereby the tendency of the door to sag exerts a force tending to press the door against the surface 31, said force acting through the coaction of the surfaces 26 and 27.

In Figs. 7 and 8, I have shown embodiments of my invention primarily intended for use in connection with swinging doors, viz., doors which may open in either direction. Thus, in Fig. 7, I have shown an edge of a door 32 to which the disc 28, having the surface 27, may be secured through the medium of the screw 29 eccentrically penetrating said disc. Upon the frame 33, I mount two discs 34 and 35 by means of journaling screws 36 and 37 whose axes are located in a common horizontal plane and are spaced apart a distance only slightly greater than the sum of the radii of said discs. The discs 34 and 35 are rotatable about their journal elements, respectively, so that their cylindrical surfaces 38 and 39, respectively, act as rollers, being engageable by the surface 27 of the disc 28. As the door 32 approaches closed position, assuming the disc 28 to be properly adjusted, the surface 27 of said disc will engage the surface 38 of the disc 34 or the surface 39 of the disc 35 at a point in the upper, outer quarter segment of such surface; and as the vertical diameter of the disc 28 moves toward the vertical diameter of the disc 34 or 35, the door 32 will be elevated. As the vertical diameter of the disc 38 passes the vertical diameter of the engaged roller, the sagging tendency of the door will urge the disc into the medium position illustrated in Fig. 7, wherein the adjacent por-

tions of the roller surfaces 38 and 39 cooperate to define a retaining cup.

In Fig. 8, I have shown a pair of discs 40 and 41 eccentrically mounted upon screws 42 and 43, respectively, whose axes are disposed in a common horizontal plane and are spaced apart a distance slightly greater than the sum of the major dimensions of said discs from the axes of said screws. Each of said discs is formed to provide a cylindrical surface 44 or 45, eccentric to the screws 42 and 43, respectively, and a further disc 46, having a cylindrical surface 47, is rotatably mounted upon a screw 47' concentrically penetrating the disc and driven into the free edge of the door 32 to cooperate with the cam surfaces 44 and 45 in a manner similar to the cooperation of the discs 28, 34, and 35 in Fig. 7.

In Figs. 9 and 10, I have shown a door edge 48 carrying a cam disc 50 secured in place by an eccentric screw 51. A lever 52 is oscillably mounted upon a screw 53 driven into the door frame 49; and one arm 54 of said lever is formed to provide a terminal socket or recess 55 adapted cooperatively to receive the disc 50. The opposite arm 56 of the lever 52 acts as a counter-weight to hold the lever 52 in a position presenting the socket 55 in the direction of door opening. Such position is substantially that illustrated in Fig. 9. As the door 48 approaches closed position, the disc 50 will enter the socket 55; and further door closing movement will cause the lever 52 to be swung in a counter-clockwise direction, thus elevating the disc 50 and the edge of the door to which it is secured. Fig. 10 illustrates the positions of the parts when the door is in closed position.

When the parts are in the positions illustrated in Fig. 10, the tendency of the door to sag presses the latch against a wall of its socket, in the manner above-described in connection with Figs. 3 and 4. If the disc 50 is oppositely arranged, as illustrated in Fig. 11, the lever 52 will be turned beyond its dead center position, and the tendency of the door to sag will press the door against its cooperating frame surface, in the manner described in the above description of Figs. 5 and 6.

In Figs. 12 and 13, I have shown a door edge 60 carrying a cam disc 61 secured in place by a screw 62. The door frame 63 mounts a lever 64 which is oscillable upon a screw 65 driven into said door frame. One arm 66 of said lever 64 is formed to provide a socket or seat 67 like the socket 55, for the reception of the disc 61. The other arm 68 of the lever 64 is formed with a notch 69 flanked by flaring stop surfaces 70 and 71. A leaf spring 72 has its free end 73 received in the notch 69. When the door is open, the spring end 73 will cooperate with the notch 69 and the stop surface 71 to hold the lever 64 resiliently in the position illustrated in Fig. 12. As the door approaches closed position, the disc 61 engages in the seat 67, and further door closing movement will shift the lever 64 in a counter-clockwise direction to lift the door edge. As the spring end 73 passes the vertical line intersecting the axis of the screw 65, the spring will act as a toggle to throw the lever 64 into the position of Fig. 13, wherein the door is resiliently held against the cooperating stop surface of the frame.

In Fig. 14, I have illustrated the ultimate in simplicity of door guiding mechanism having the operative advantages inherent in the use of a

cam disc of the character herein disclosed. In that embodiment of my invention, I have shown a door 75 and a frame member 76, with a disc 77 mounted upon the door edge by means of an eccentric screw 78; and a simple bracket 79 secured to the frame member 76 by screws 80, said bracket being formed to provide an upwardly presented plane surface 81, inclined upwardly in a door closing direction. The disc 77, when properly adjusted upon the screw 78, will engage the lower portion of the surface 81 as the door approaches closed position, and will ride upwardly on said surface as the door is moved to final closed position, to correct any door sag.

In Fig. 15, I have shown a door 82 carrying a disc 83 eccentrically mounted upon a screw 84; and a frame member 85 to which is secured a bracket 86, by means of screws 87. The bracket 86 presents oppositely upwardly inclined plane surfaces 88 and 89, separated by a cupped surface 90. This structure is adapted for use with ordinary doors or with swinging doors. In the latter association, the cam 83 will engage alternatively with the surfaces 88 and 89, depending upon the direction in which the door has been opened.

In Fig. 16, I have shown fragments of a door 91 and a frame 92, the door edge carrying a disc 93 eccentrically mounted upon a screw 94. A bracket 95 is secured to the frame member by means of screws 96, or the like, and is formed to provide a socket, opening in the direction of door-opening movement, and bounded by flaring surfaces 98 and 99. If the door sags, the cam disc 93 will ride up the surface 99 as the door closes; or if the frame has been warped so that the free edge of the door tends to assume a position above normal position, the cam disc will ride down the surface 98, as the door closes.

It will be clear that any one of the embodiments of the invention disclosed herein may be so proportioned and adjusted as to pull the free edge of the door downwardly, instead of lifting it upwardly, as the door moves to closed position, if conditions so demand. It will also be obvious that, although I have shown the elements 24 and 28, for instance, mounted upon and projecting beyond the surfaces of the frame and door, either the door or the frame may be recessed to accommodate the cooperating elements, in case the door fits its frame too closely to permit interposition of the parts between the door and its frame.

I claim as my invention:

1. A door guide for use with a door and its frame comprising an element mounted on the free vertical edge of such door and an element mounted on the associated edge of the door frame in position to be engaged by said door-mounted element, as the door approaches closed position, one of said elements being adjustably mounted upon an eccentric horizontal axis.

2. A door guide for use with a door and its frame comprising an element formed to provide a surface inclined out of the horizontal in a door-closing direction and a second element formed to provide a curved surface, means for securing one of said elements to said frame, means for securing the other of said elements to the free vertical edge of said door in position to cause said element surfaces to engage cooperatively as said door approaches closed position, the securing means for said second element including a journal member penetrating said second element on a line parallel with said curved surface but eccentric relative thereto.

3. A door guide for use with a door assembly

consisting of a frame member and a closure member, said guide comprising a circular disc, a journal member for concentrically rotatably mounting said disc on one of said door members, a second circular disc, a journal member for eccentrically mounting said second disc on the other of said door members in a position for engagement of edge surfaces of said discs as the closure member approaches closed position, and means for securing said second disc in any desired position of rotational adjustment about its journal member.

4. A door guide for use with a door and its frame comprising an element mounted on said frame and a second element mounted on the free edge of said door, said elements being engageable and cooperable, upon closure of said door, to lift said free edge of said door, one of said elements being eccentrically mounted for adjustment to vary the vertical position, relative to its support, of that portion of its surface which engages the other of said elements.

5. A door guide for use with a door and its frame comprising means mounted on said frame and providing a surface upwardly inclined in a door-closing direction and an upwardly-opening cupped surface merging with the upper end of said inclined surface, an element mounted on the free edge of said door for cooperative engagement with said means as said door approaches closed position, said element presenting a curved surface for engagement with said surfaces of said means, and journal means supporting said element on said door for adjustment about an axis parallel with said curved surface but eccentric relative thereto.

6. The door guide of claim 3 in which the vertical diameter of the closure-mounted disc, when the closure is in fully closed position, is disposed between the vertical diameter of the frame-mounted disc and a surface of the frame facing in the direction of door-opening movement.

7. The door guide of claim 3 in which the vertical diameter of the frame-mounted disc, when the closure is in fully closed position, is disposed between the vertical diameter of the closure-mounted disc and a surface of the frame facing in the direction of door-opening movement.

8. A door guide for use with a door and its frame comprising a lever pivotally mounted on that surface of said frame which faces the free edge of said door when the door is closed, an end of said lever being formed with a socket, means biasing said lever, when the door is open, to present said socket toward the open door, and an element mounted on said free edge of said door at a level to enter said lever socket at said door approaches closed position and to swing said lever end upwardly and in the direction of door-closing movement upon further closing movement after said element enters said socket.

9. The door guide of claim 8 in which said element is mounted for eccentric adjustment about a horizontal axis.

10. The door guide of claim 8 in which said element is a circular disc, and including a journal element eccentrically penetrating said disc upon a line parallel with the axis of said disc and perpendicular to said door edge.

11. The door guide of claim 8 in which said biasing means is a counterweight.

12. The door guide of claim 8 in which said biasing means is a toggle spring acting, when said lever is carried past a neutral position by door-

closing movement, to bias said lever in an opposite direction.

13. A door guide comprising an element adapted to be fixed to that surface of a door frame which faces the free edge of a door when said door is closed, said element providing an upwardly presented surface inclining upwardly in the direction of door-closing movement, a circular disc adapted to be fixed to the free edge of such door, and a journal element penetrating said disc on a line eccentric with respect to the axis of said disc to support said disc for rotational adjustment about the axis of said journal element.

14. A door guide for use with a door and its frame comprising a device mounted on the free vertical edge of such door and a device mounted on the associated edge of the door frame in position to be cooperatively engaged by said door-mounted element, as the door approaches closed position, one of said cooperating devices provid-

ing two surfaces inclined from the horizontal and symmetrically flaring toward the other of said devices, and the other of said devices comprising a disc mounted upon an eccentric horizontal axis transverse to said surfaces and located between the planes of said surfaces.
